UNITED STATES PATENT OFFICE.

RICHARD WHITAKER, OF NEW BRUNSWICK, NEW JERSEY, ASSIGNOR TO
THE NEVERSLIP MANUFACTURING COMPANY, OF SAME PLACE.

DESIGN FOR A HORSESHOE-PAD.

SPECIFICATION forming part of Design No. 29,581, dated November 1, 1898.

Application filed October 6, 1898. Serial No. 692,860. Term of patent 7 years.

To all whom it may concern:

Be it known that I, RICHARD WHITAKER, a citizen of the United States, residing at New Brunswick, in the county of Middlesex and State of New Jersey, have invented and produced a new and original Design for Horseshoe-Pads; and I do hereby declare the following to be a full, clear, and exact description of the same, reference being had to the accompanying drawings, forming a part thereof.

In said drawings, Figure 1 is a bottom face view of a horseshoe-pad embodying my new design. Fig. 2 is a vertical cross-section on line $\alpha\alpha$ of Fig. 1.

The object of my invention is to provide a design for horseshoe-pads; and to this end said invention consists in the design as herein set forth and shown.

The leading features of my design for a pad consist in a horseshoe-shaped front portion terminating in a heel portion, the front of said heel having two scallops of the same length, the horseshoe-shaped cavity in the pad terminating against said two scallops and containing two concentric rings, with a shield within

the inner ring, the pad being also provided with rows of semispherical projections upon its face.

The pad consists of a horseshoe-shaped back- 30 ing A, to which is secured the pad proper, B, the front portion of which is horseshoe-shaped and is beveled inwardly and outwardly and terminates in the heel portion C. The front of said heel has two beveled scallops $c c$, hav- 35 ing their dividing-line in the axis of the heel. The face of the pad is provided with rows of semispherical projections b , and within the cavity of the pad and projecting in relief from its inner wall are two concentric rings 40 d , with a shield e within the inner ring.

Having fully described my invention, I claim—

The design for a horseshoe-pad as herein shown and described. 45

In testimony whereof I affix my signature in presence of two witnesses.

RICHARD WHITAKER.
